BABY CARRIAGE WITH COLLAPSIBLE DASHER

Helmer W. Wickman and George A. J. Racine,
Gardner, Mass., assignors to Heywood-Wake-
field Company, Gardner, Mass., a corporation
of Massachusetts

Application June 5, 1948, Serial No. 31,304

6 Claims. (Cl. 280—36)

1

The present invention relates in general to baby carriages and in particular to baby carriages of the folding type, such as strollers, wherein the parts of the carriage body are collapsed into substantially flat condition above the running gear, by swinging the pusher handle downwardly into a position wherein the parts of the carriage above the running gear will occupy a minimum amount of space.

Baby carriages of the above described type are usually provided with a dasher movably mounted at the front of the carriage, the dasher being of open bucket-like form so as to receive the feet of the occupant when in a reclining or sitting position. It is customary to provide means for manually adjusting the dasher with respect to the carriage body, so as to maintain the dasher in a substantially horizontal position, as when the occupant is reclining, and in a turned down position, as when the occupant is sitting in the carriage with its feet inside the dasher. Should it be desired to collapse the carriage with the dasher in its raised or horizontal position, it is first necessary to release the dasher in order to permit the parts to be folded down without straining and possibly tearing the flexible upholstery of the body, and experience has shown that many carriages are damaged in this way through failure to release the dasher manually before swinging down the pusher handle to move the parts into collapsed condition.

The object of the present invention is to provide a baby carriage construction of the collapsible type wherein the dasher is so connected to the pusher handle that it will be automatically swung downwardly clear of the folding parts of the body, should the pusher handle be moved to collapse the carriage with the dasher in its horizontal position wherein it is disposed adjacent to the sides of the body to receive the feet of the reclining occupant. In addition, the connection between the dasher and the collapsible pusher handle is such that the carriage can be collapsed or extended independently of the dasher, in the event that the dasher already occupies its folded down position.

The above and other advantageous features of the invention will hereinafter more fully appear from the following description, with reference to the accompanying drawings in which:

Fig. 1 is a perspective view of a collapsible baby carriage equipped with a dasher operating mechanism embodying the present invention.

Fig. 2 is a view in side elevation showing the connection of the dasher to the pusher handle

2

when the dasher occupies a horizontal position, with parts of the running gear of the carriage being shown in dotted lines in order to simplify the drawing.

Fig. 3 is a view in side elevation of the parts of Fig. 2 in a collapsed position.

Fig. 4 is a view in front elevation of the carriage shown in Fig. 2, with parts of the running gear being removed to show the connection of the dasher, and with the dasher being partially broken away to show the inside of the carriage body.

Referring first to Fig. 1, the invention is shown, for purposes of illustration, as being embodied in a baby carriage of the folding type, having a running gear of conventional construction comprising front and rear axles 1 and 2 carrying wheels 3. The axles 1 and 2 are connected together and held in spaced parallel relation by springs 4 extending lengthwise of the carriage on each side.

The upwardly and inwardly curved ends of the springs 4 provide a yieldable support for the carriage body generally indicated at B, with the ends of the springs being connected by shackles 5 to a pair of spaced parallel body frame members 6. These frame members 6 are connected together by cross members 7 which serve to support between them a pair of spaced side bars 8, with the cross members 7 and bars 8 constituting a bottom for the carriage body B. The body B also comprises upwardly extending side panels 9, composed of flexible material, and a back 10 that is mounted on pivots 11 provided by brackets 12 attached to the rear ends of the side bars 8, so that the back 10 can be swung into different positions between the side panels 9, as indicated in full and dotted lines in Fig. 2.

The carriage body B also provides a dasher 13 of open bucket-like form, and one edge of the dasher 13 provides projecting arms 14, the ends of which are connected by pivots 15 to brackets 16 attached to the front ends of the side bars 8. The dasher 13 is adapted to be swung about its pivots 15 either into the position of Fig. 2, wherein the dasher forms a closure for the end of the carriage body in cooperation with the side panels 9, or into the position of Fig. 3, wherein the dasher 13 extends below the body so as to receive the feet of an infant supported in a sitting position by the back 10. As best shown in Fig. 1, and in back of the broken away front portion of the dasher 13 in Fig. 4, the side panels 9 and back 10 are connected together by flexible gussets 17 and the side panels 9 are also con-

ected at their lower edges to the covering of a seat 18 which provides an apron 19 extending into the dasher 13, see Fig. 3. It is the object of the present invention to provide an arrangement for insuring that the dasher 13 will always be moved downwardly into the position of Fig. 3 whenever the carriage is collapsed, so as to prevent the interconnected flexible portions of the upholstery described above from being subjected to strains which might result in tearing the same.

The carriage is adapted to be propelled by means of a pusher handle 20 of U-shape form, and the downwardly extending sides 20a of the handle 20 are connected by pivots 21 at their lower ends to upwardly extending portions 6a of the side frame members 6. Each handle side 20a carries a bracket 22 pivoted at 23 a short distance above the pivot 21, and this bracket 22 serves as a support for one end of a side arm 24 that extends forwardly and serves to hold a side panel 9 in a vertical plane when the carriage is in an extended position. The forward ends of the side arms 24 are curved downwardly so as to generally conform to the shape of the associated side panels 9, and the lower end of each arm 24 is connected by a pivot 25 to the upper end of a lever 26 turnable on a fixed pivot 27 provided by the side frame member 6.

The ends of the two levers 26 which extend below the fixed pivots 27 are connected by a cross-bar 28, best shown in Fig. 4, and this crossbar 28 carries a slotted plate 29 adapted to receive a notch 30a provided near the end of a latch arm 30. The opposite end of the arm 30 is turnable on a pivot 31 carried by a bracket 32 secured to the underside of the dasher 13. The latch arm 30 provides a handle 33 extending forwardly from the dasher 13, when it occupies the position of Fig. 2, whereby the latch arm 30 may be disengaged manually from the crossbar 28 when it is desired to lower the dasher 13, without collapsing the carriage.

As previously pointed out, Fig. 2 illustrates the position of the parts of the carriage when it is being used to support its occupant in a reclining position, with the dasher 13 then being positively held where it is disposed entirely above its pivots 15, with the sides of the dasher in substantial alignment with the side panels 9, so as to provide, in effect, a closed body. In this position of parts, the pusher handle 20 extends rearwardly at its upper end, and when the carriage is being propelled by the pusher handle 20, relative pivotal movement between the handle 20 and the side arms 24 is prevented by a latch 34 pivotally mounted on one handle side 20a and held in engagement with a fixed stop 35 by a spring 36. By raising the latch 34 from the position of Fig. 2, the pusher handle 20 can be swung forwardly about its pivots 21 in the direction of the dasher 13 in Fig. 2, in order to collapse the carriage and to simultaneously depress the dasher 13, as will next be described.

Assuming that the parts occupy the position of Fig. 2 when the latch 34 is lifted to disengage it from the stop 35, downward turning movement of the handle 20 about its pivots 21 will cause the side arms 24 to move forwardly and downwardly as the arms 24 swing on the bracket pivots 23 which are located above the handle pivots 21. This movement will continue until the sides 20a of the handle 20 reach an extreme position in which the closed end of the handle engages the folded down arms 24, as shown in Fig. 3. With the handle 20 in its lowermost

position, the curved ends of the arms 24 occupy a position below the level of the handle, wherein the levers 26 will have been turned about their fixed pivots 27 to position the inner ends of the levers at a point just below the frame members 6. As the levers 26 move into the position of Fig. 3, the crossbar 28, which connects the levers, will carry the latch arm 30 upwardly to swing the dasher 13 downwardly about its pivots 15 until it occupies the position of Fig. 3, wherein the dasher 13 extends forwardly of the running gear, entirely out of the way of the ends of the arms 24.

It will be readily understood from the above description of the operation of the handle 20 that as soon as the handle 20 starts its downward movement from the extended position of Fig. 2 into the collapsed position of Fig. 3, the dasher 13 will also start to swing downwardly in response to turning movement of the levers 26 in a counterclockwise direction, as viewed in Fig. 2. Consequently, by the time the handle 20 and the connected side arms 24 are fully collapsed, as shown in Fig. 3, the dasher is entirely out of the way of the handle and side arms, and the space above the seat 18 is entirely clear to permit folding down the back 16 to overlie the seat.

As a result of the above described connection between the dasher 13 and the handle 21, the conversion of the carriage from an extended to a collapsed condition can always be made with the assurance that the dasher will be automatically removed from the raised position of Fig. 2, so that there will be no possibility of any of the body parts interfering with the dasher, or of subjecting the flexible portions of the upholstery, such as the gussets 17, to any strain or pull which might tear or otherwise damage the material. When the carriage is converted from a collapsed to an extended condition, the dasher 13 is not returned to the position of Fig. 2 until the side arms 24 and handle 20 are fully extended, so that here again, there is no possibility of damaging the upholstery.

As previously noted, the dasher 13 can be disconnected from the handle 20 at any time by manually lifting the latch arm 30 to disengage its notch 30a from the plate 29 on crossbar 28, through the application of pressure to the handle 33. When this occurs, the dasher 13 will be free to swing downwardly to the position of Fig. 3. With the dasher thus disconnected from the handle 20, the latter can be swung downwardly to a collapsed position, at any time, without interference between any of the operating parts. Obviously, the dasher will remain in its unlatched position with its latch arm 30 extending underneath the bottom bar 8, as long as it is desired to employ the vehicle as a stroller in which the occupant sits on the seat 18, with its feet in the dasher.

From the foregoing, it is apparent that by the present invention, there is provided an improved baby carriage construction of the collapsible type characterized by the fact that the dasher will be automatically swung downwardly clear of the folding parts of the carriage whenever the pusher handle is moved to collapse the carriage, with the dasher occupying a position wherein it is disposed to receive the feet of a reclining occupant.

We claim:

1. In a baby carriage, the combination with 75 running gear for supporting a carriage body com-

prising a pusher handle and side arms pivotally mounted with respect to the running gear so that the carriage can be converted from an extended to a collapsed condition, and a dasher pivotally mounted at the front of the running gear and positionable so as to receive the feet of the carriage occupant when in a reclining or sitting position, of a connection between said dasher and said side arms extending across the running gear below the pivotal mounting of said dasher, whereby said dasher is automatically lowered with respect to the running gear whenever said handle and said side arms are moved to convert the carriage from an extended to a collapsed condition.

2. In a baby carriage, the combination with running gear for supporting a carriage body comprising a pusher handle and side arms pivotally mounted with respect to the running gear so that the carriage can be converted from an extended to a collapsed condition, and a dasher pivotally mounted at the front of the running gear and positionable so as to receive the feet of the carriage occupant when in a reclining or sitting position, of a connection between said dasher and said side arms extending across the running gear below the pivotal mounting of said dasher for maintaining said dasher in a raised position to receive the feet of a reclining carriage occupant, with said connection serving to automatically lower said dasher within the running gear to prevent its engagement with parts of the body, in advance of movement of said handle and side arms from an extended to a collapsed position.

3. In a baby carriage, the combination with running gear having parts of a folding body mounted thereon comprising side panels, a back and a seat, with said body parts being connected together by flexible material, means for maintaining said body parts in either an extended or a collapsed condition and an open dasher pivotally mounted on the running gear so as to receive the feet of the occupant of the carriage in either reclining or sitting position, of a connection between said dasher and the sides of said body and extending across the running gear below the pivotal mounting of said dasher for maintaining said dasher in position to provide a closed end for the body when said sides are extended, with said connection serving to automatically shift said dasher out of the way to permit folding of the flexible material of said body, without strain, when converting the parts of the body from an extended to a collapsed condition.

4. In a baby carriage, the combination with running gear for supporting the parts of a folding body comprising a pusher handle, side arms and a back pivotally mounted with respect to the running gear, so that the carriage can be converted from an extended to a collapsed condition, with flexible material carried by the side

arms being also connected to said back, and a dasher pivotally mounted at the front of the running gear and positionable so as to receive the feet of the carriage occupant when in a reclining or sitting position, of a connection between said dasher and said side arms extending across the running gear below the pivotal mounting of said dasher for maintaining said dasher in a raised position to provide a closed end for the body in cooperation with the extended side arms, with said connection serving to automatically lower said dasher within the running gear whenever said handle and side arms are moved to convert the carriage from an extended to a collapsed condition, to permit folding of the flexible material of the body without interference with said dasher.

5. In a baby carriage, the combination with running gear for supporting the parts of a folding body comprising a pusher handle, side arms and a back pivotally mounted with respect to the running gear, so that the carriage can be converted from an extended to a collapsed condition, with flexible material carried by the side arms being also connected to said back, and a dasher pivotally mounted at the front of the running gear and positionable so as to receive the feet of the carriage occupant when in a reclining or sitting position, of a connection between said side arms extending across the running gear, below the pivotal mounting of said dasher, and a latch arm connecting said dasher to said cross connection for causing said dasher to move simultaneously with said handle and side arms when converting said body from an extended to a collapsed condition or vice versa.

6. In a baby carriage, the combination with running gear for supporting the parts of a folding body comprising a pusher handle and side arms pivotally mounted with respect to the running gear, so that the carriage can be converted from an extended to a collapsed condition, and a dasher pivotally mounted at the front of the running gear and positionable so as to receive the feet of the carriage occupant, of a connection between said side arms extending across the running gear, below the pivotal mounting of said dasher, and a latch member connecting said dasher to said cross connection for causing said dasher to swing downwardly with said handle and side arms when converting said body from an extended to a collapsed condition.
